ATTORNEYS

UNITED STATES PATENT OFFICE.

ANTONIO FALCONE, OF BLOOMFIELD, NEW JERSEY.

FRUIT-CRUSHER AND JUICE-EXTRACTOR.

1,356,199.

Specification of Letters Patent. Patented Oct. 19, 1920.

Application filed July 25, 1919. Serial No. 313,200.

To all whom it may concern:

Be it known that I, ANTONIO FALCONE, a citizen of the United States, residing at Bloomfield, in the county of Essex and State of New Jersey, have invented certain new and useful Improvements in Fruit-Crushers and Juice-Extractors; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in that class of implements used more particularly in the household for crushing fruits, and the like; and, the present invention has reference, more particularly, to a novel and simply constructed apparatus which is especially adapted for crushing tomatoes and removing the seed therefrom, but which may also be readily employed for crushing berries of the various kinds and for removing the seeds or pits therefrom.

The present invention has for its principal object to provide a novel and simply constructed implement or apparatus of the general character hereinafter set forth, which can easily be manipulated for the purposes above stated, which is readily applied to a vessel for the reception of the crushed fruit or pulp; and, furthermore, to provide a fruit-crushing device which can easily be kept clean.

Other objects of the present invention not at this time more particularly enumerated will be clearly understood from the following description of the present invention.

With the various objects of the present invention in view, the said invention consists, primarily, in the novel fruit-crusher and strainer hereinafter set forth; and, the invention consists, furthermore, in the novel arrangements and combinations of the various devices and parts, as well as in the details of the construction of the said parts, all of which will be more fully described in the following specification, and then finally embodied in the clauses of the claims which are appended to and which form an essential part of the said specification.

The invention is illustrated in the accompanying drawings, in which:

Figure 1 is a plan view of a fruit-crusher and strainer showing one embodiment of the principles of the present invention, and representing the same in its operative position placed above a receiving vessel, the latter being also shown in plan or top view; Fig. 2 is a longitudinal vertical section taken centrally through the devices and parts represented in said Fig. 1; and Fig. 3 is a transverse vertical section of the same, said section being taken on line 3—3 in said Fig. 2.

Similar characters of reference are employed in the above described views, to indicate corresponding parts.

Referring now to the several figures of the drawings, the reference-character 1 indicates one form of fruit-crusher and strainer, made according to and embodying the principles of the present invention, the same comprising a main receiving shell consisting of a pair of end-members 2 and 3, and an intermediately disposed member 4, of semi-circular cross-section, substantially as shown in Fig. 3 of the drawings. The upper and open portion of the fruit-receiving element thus provided is preferably bounded by the outwardly flaring marginal portions 5, 6, 7 and 8, connected with 2, 3 and 4, substantially as illustrated.

That the said body of the apparatus may be disposed above a suitable receiving vessel, as 9, the said body is provided with suitably disposed supporting bars, as 10 and 11, connected by the bracing members or bars 12, said members or bars being of sufficient length and being arranged in a suitable manner, that they can be made to rest upon the upper marginal edge-portions 13 of the vessel 9, substantially as shown. The said member 4 is provided with a multiplicity of holes or perforations 14, or other suitable mesh.

The end-members 2 and 3 hereinabove mentioned, are provided with suitably formed holes or perforations 15 and 16, providing bearings in which is rotatably mounted a rod or shaft 17, its one end being of such length that it will extend into and form an opening 18 with which one of the said bracing members or bars 12 is pro-

- vided, as shown in Fig. 2 of the drawings, and the said projecting end-portion of the said rod or shaft 17 has suitably secured thereon, a crank or handle, as 19.
- 5 The said shaft or rod 17 is also provided upon its portion which is located between the two end-members 2 and 3, with oppositely projecting arms 20 and 21, the respective arms 20 carrying a longitudinally extending bar 22, and the respective arms 21 likewise carrying a longitudinally extending bar 23, the said bar 22 being provided with a plurality of flat and arc-shaped crushing fingers 24, and the bar 23 being provided with a plurality of flat and arc-shaped crushing fingers 25. From an arrangement of Fig. 3 it will be seen, that the centers of the arcs of said crushing fingers 24 and 25 lie on opposite sides, horizontally, 15 of the central longitudinal axis of the rod or shaft 17, whereby the said fingers when lying in or passing through the lower arc-shaped or semi-cylindrical portion of the member 4 of the body will lie in different 20 planes, that is while the flat ends 26 of the respective fingers move in close juxtaposition to the inner curved surface-portion of the member 4, the portion 27 of said fingers move in arcs farther removed from the said 25 inner curved surface-portion of the member 4, so as to roll or squeeze the fruit into and between the more widely separated parts and gradually and finally crushing the same between the more closely located parts, and 30 the sweeping action of the fingers forcing the juice and pulp, as with tomatoes, into and through the mesh or many holes with which the member 4 is provided, when the shaft and its crushing fingers are actuated 35 so as to move in the direction of the arrow X indicated in said Fig. 3 of the drawings.
- The operation of the device for crushing fruits and for extracting the juices therefrom, as well as straining the same, will be 40 readily understood from an inspection of the several figures of the drawings, and any further description of the same is therefore deemed unnecessary.
- I claim:—
- 50 1. A fruit-crusher and juice-extractor comprising a body having end-members and an intermediately disposed member of semi-circular cross-section, said latter member being formed with a multiplicity of openings or perforations, supporting members extending longitudinally from the ends of said body for resting the same upon a receiving vessel, a shaft extending longitudinally within said body and rotatably mounted in bearing-positions in said end-members,
- 55 60

means for rotating said shaft, arms projecting on opposite sides of said shaft, longitudinally extending bars connected with the ends of the respective arms upon each side of the shaft, and a series of flat arc-shaped crushing fingers extending from each bar, said fingers alternating with spaces between them.

2. A fruit-crusher and juice-extractor comprising a body having end-members and an intermediately disposed member of semi-circular cross-section, said latter member being formed with a multiplicity of openings or perforations, supporting members extending longitudinally from the ends of said body for resting the same upon a receiving vessel, a shaft extending longitudinally within said body and rotatably mounted in bearing-positions in said end-members, means for rotating said shaft, arms projecting on opposite sides of said shaft, longitudinally extending bars connected with the ends of the respective arms upon each side of the shaft, and a series of flat arc-shaped crushing fingers extending from each bar, said fingers alternating with spaces between them, the arc-shaped portions of said fingers being eccentrically disposed with relation to the inner arc-shaped surface of said intermediately disposed member.

3. A fruit-crusher and juice-extractor comprising a body having end-members and an intermediately disposed member, said latter member being formed with a multiplicity of openings or perforations, supporting members extending from the ends of said body, and a cross-bar between each pair of supporting members, one of said cross-bars having a shaft-receiving opening, a shaft extending longitudinally within said body and rotatably mounted in bearing-positions in said end-members and having a portion extending into and through the opening in said cross-bar, means for rotating said shaft, and a series of arc-shaped flat crushing fingers connected with and extending from said shaft, said fingers alternating with spaces between them, the arc-shaped portions of said fingers being eccentrically disposed with relation to the inner arc-shaped surface of said intermediately disposed member.

In testimony that I claim the invention set forth above I have hereunto set my hand this 22nd day of July, 1919.

ANTONIO FALCONE.
